UNITED STATES PATENT OFFICE.

TOWNER K. WEBSTER, JR., OF EVANSTON, ILLINOIS, ASSIGNOR, BY MESNE ASSIGNMENTS, TO AMERICAN STEAM CONVEYOR CORPORATION, OF CHICAGO, ILLINOIS, A CORPORATION OF NEW YORK.

ASH-CONVEYER.

1,252,522.

Specification of Letters Patent. Patented Jan. 8, 1918.

Application filed August 28, 1916. Serial No. 117,200.

To all whom it may concern:

Be it known that I, TOWNER K. WEBSTER, Jr., a citizen of the United States, residing at Evanston, in the county of Cook and 5 State of Illinois, have invented a certain new and useful Improvement in Ash-Conveyers, of which the following is a full, clear, concise, and exact description, reference being had to the accompanying drawings, forming 10 a part of this specification.

My invention relates to ash conveyers of the type wherein steam or other fluid under compression is passed through a conduit for conducting ashes through the same conduit 15 from a source of ash supply, such as a boiler, or boiler room, to an ash hopper or receptacle adapted and located so that the contents thereof may easily be removed. A portion of the steam used in such a system is condensed in the ashes while the remainder is 20 permitted to escape from the receptacle through a vent opening, usually located at the top thereof. The steam does not upon entering the ash receptacle deposit all of the 25 ashes transmitted through the conduit, but retains a considerable quantity of very fine ashes or ash dust which passes through the vent opening with the remaining steam. The pollution of the atmosphere in this manner is, of course, objectionable and particularly so in congested districts. This objection 30 can be partially overcome by installing a long vent pipe leading from the ash hopper to the top of a high building. Such an installation is, however, quite an expense and furthermore is unsightly in appearance.

It is the object of my invention to provide efficient and economical means for acting upon the escaping steam and ash dust and 35 ultimately depositing the dust in concrete form in a separate and distinct tank which is easily accessible and which can be cleaned without the necessity of entering the chamber from which the ash dust is expelled to 40 the tank. These and other objects of my invention will be more fully pointed out in connection with the accompanying drawings in which—

Figure 1 is an elevational view of a boiler 45 room and ash conveyer which is provided with the system of our invention, some of the parts being illustrated in section to more clearly show their construction; and

Fig. 2 is a fragmentary detailed vertical 50 cross-sectional view of the chamber herein-

after referred to as the condensing or mixing chamber.

Similar characters of reference refer to similar parts throughout both views.

In Fig. 1, 3—3 indicates a plurality of 60 boilers positioned side by side provided with the furnaces 4—4. Disposed below the level of the floor of the boiler room and running parallel with the front ends of the furnaces is a conduit 5 and provided at one end with 65 an upwardly turning elbow 6 communicating with the conduit 7. The upper end of the conduit 7 empties into an ash hopper or receptacle 8 preferably held, as shown, upon a support 9 above the ground. The lower 70 end of the hopper carries a trap door 10 which when opened permits the removal of ashes from the hopper into a vehicle or other container positioned under the hopper.

The conduit 5 is provided with a plurality 75 of intake T's 11—11 positioned in front of the several furnaces. Each intake T is provided with a plate normally closing the opening of the upwardly extending arm of the T. Extending upwardly within the elbow 6 is a steam injector 12 connected by a pipe 13 with any suitable steam supply such, for example, as the boiler 3. A valve 14 is provided in the pipe 13 which when opened permits the passage of steam through the injector 12 and upwardly through the conduit 7 into the hopper 8. As the steam is thus projected upwardly across the horizontally lying conduit 5 a vacuum or reduction of pressure is created in the conduit 5 so that 80 upon removing one of the cover plates provided in the T's and the insertion of ashes in such intake T the ashes will be conducted upwardly into the receptacle or hopper 8.

During this transportation of the ashes 85 from the boiler room to the hopper a small portion of the weight of steam employed is condensed in the ashes while the remainder is permitted to escape through a vent pipe illustrated at 15. This escaping steam has 90 adhering to it a considerable quantity of very fine ashes or ash dust which is finally deposited in a second tank by the means I will now describe.

The vent pipe 15 preferably extends down- 95 wardly from the hopper and has attached thereto a pipe 16 forming a condensing or mixing chamber. The lower end of this pipe communicates with a T 17 through the horizontal arm of which a water supply 100

113

pipe 18 extends. Positioned under the lower arm of the T 17 is the ash dust tank 20 provided at its upper end with an overflow pipe 21 the purpose of which will be presently described.

The water supply pipe 18, as most clearly illustrated in Fig. 2, communicates with a nozzle pipe 22 extending longitudinally within the condensing pipe 16 and is provided along its length with a plurality of small outlet openings 23 arranged to project cold water in fine streams into the condensing or mixing pipe 16.

The operation of the devices is as follows: As the steam and ash dust enters the mixing or condensing chamber 16 the steam is condensed and the ash dust intermingled with the water supplied through the nozzle 22. As the water flows out through the lower arm of T 17 it carries with it the condensed steam and the ash dust which adhered to the steam before the condensation took place and flows into the concreting tank 20. The concreting tank 20 is constructed of such size and shape that very little agitation is produced in the tank during the flow of water from the condensing chamber to the tank so that the ash dust is permitted to gradually sink to the bottom thereof in concrete form. On account of the overflow pipe 21 the clear water is allowed to flow away and leave behind it the dust. When a sufficient quantity of dust has collected in the tank it can be easily removed without entering the condensing or mixing chamber 16, as is apparent from Fig. 1 of the drawings.

Having thus described my invention what I claim as new and desire to secure by Letters Patent of the United States is:

1. An ash conveyer comprising an ash receptacle, a conduit having one end thereof communicating with the ash receptacle and its other end adapted to receive ashes to be transmitted to the receptacle, a steam nozzle in the conduit intermediate the ends thereof and arranged to direct steam through the conduit into the receptacle, whereby the ashes are conducted by the steam to the ash receptacle, a steam condensing chamber communicating with the upper part of the ash receptacle, a nozzle in said chamber arranged to project water against the steam and ash dust entering the condensing chamber from the ash receptacle to condense the steam and intermingle with the ash dust, and an ash dust concreting tank separate from the condensing chamber and arranged to receive from the chamber, in one mass, the water supplied through the nozzle, the condensed steam and the ash dust, said tank being arranged to permit overflow of water at its upper portion, whereby the ash dust settles in the bottom of the tank in a con-

crete form and the clear water passes off at 65 the top of the tank.

2. An ash conveyer comprising an ash receptacle, a conduit having one end thereof communicating with the ash receptacle and its other end adapted to receive ashes to be 70 transmitted to the receptacle, a nozzle in the conduit intermediate the ends thereof and arranged to direct a fluid through the conduit into the receptacle, whereby the ashes are conducted by the fluid to the ash receptacle, a mixing chamber communicating with the upper part of the ash receptacle, means in said chamber arranged to project water against the ash dust entering the mixing chamber from the ash receptacle to intermingle the ash dust with the water, and an 75 ash dust tank separate from the mixing chamber arranged to receive from the chamber the water supplied through the said means, and the ash dust, said tank being arranged to permit overflow of water at its upper portion, whereby the ash dust settles in the bottom of the tank and the clear water passes off at the top thereof.

3. An ash conveyer comprising an ash 90 receptacle, a conduit having one end thereof communicating with the ash receptacle and its other end adapted to receive ashes to be transmitted to the receptacle, a nozzle arranged to direct fluid under compression 95 through the conduit into the receptacle, whereby the ashes are conducted by the fluid to the ash receptacle, a mixing chamber communicating with the upper part of the ash receptacle, a nozzle in said chamber arranged to project water against the ash dust entering the mixing chamber from the ash receptacle to intermingle the ash dust with the water, and an ash dust tank separate 100 from the mixing chamber arranged to receive from the chamber the water supplied through the nozzle and the ash dust, said tank being arranged to permit overflow of water at its upper portion, whereby the ash dust settles in the bottom of the tank and the clear water passes off at the top thereof.

4. An ash conveyer comprising an ash receptacle, a conduit having one end thereof communicating with the ash receptacle and its other end adapted to receive ashes to be 115 conducted to the receptacle, a steam nozzle arranged to direct steam through the conduit into the receptacle whereby the ashes are conducted by the steam to the ash receptacle, a steam condensing chamber communicating with the upper part of the ash receptacle, a nozzle in said chamber arranged to project water against the steam and ash dust entering the condensing chamber from the ash receptacle to condense the steam and intermingle with the ash dust, and an ash dust concreting tank separate from the condensing chamber and arranged to receive 120

125

from the chamber, in one mass, the water supplied through the nozzle, the condensed steam and the ash dust, said tank being arranged to permit overflow of water at its upper portion whereby the ash dust settles in the bottom of the tank in a concrete form and the clear water passes off at the top thereof.

5. An ash receptacle and a steam ash conveyor in which the ashes and steam are both conducted to the ash receptacle, having a vent pipe communicating with the receptacle and arranged to receive from the receptacle the utilized steam and the ash dust which still adheres thereto, and a second pipe extending longitudinally within the first pipe and provided with a plurality of outlets along its length arranged to project streams of water into the first pipe, whereby the steam in the first pipe is condensed and the ash dust intermingled with the water.

10. An ash receptacle and a steam ash conveyor in which the ashes and steam are both conducted to the ash receptacle, having a vent pipe communicating with the receptacle and arranged to receive from the re-

ceptacle the utilized steam and ash dust which still adheres thereto, a second pipe extending longitudinally within the first pipe and provided with a plurality of outlets along its length arranged to project streams of water into the first pipe whereby the steam in the first pipe is condensed and the ash dust intermingled with the water, said first pipe being provided at its lower portion with an outlet arranged to expel from the pipe in one mass the water supplied to the second pipe, the condensed steam and ash dust, and a tank located under the outlet to receive the water and dust, said tank being arranged to permit overflow of water at its upper portion, whereby the ash dust settles in the bottom of the tank in a concrete form and the clear water passes off at the top thereof.

15. In witness whereof, I hereunto subscribe my name this 21st day of August, A. D. 1916.
